UNITED STATES PATENT OFFICE.

GEORGE LLEWELLYN DAVIES AND WALTER EDWIN WINDSOR RICHARDS, OF LONDON,
ENGLAND.

PROCESS FOR THE TREATMENT OF COAL-TAR.

1,148,011.

Specification of Letters Patent.

Patented July 27, 1915.

Application filed July 18, 1910. Serial No. 572,636.

To all whom it may concern:

Be it known that we, GEORGE LLEWELLYN DAVIES, civil engineer, and WALTER EDWIN WINDSOR RICHARDS, mining engineer, both subjects of the King of Great Britain, residing at 72 and 73 Hop Exchange, London, England, and 43 Sinclair road, Kensington, London, England, respectively, have invented a certain new or Improved Process for the Treatment of Coal-Tar, of which the following is a specification.

This invention relates to a new or improved process for the treatment of coal tar; and the invention has for its object (*inter alia*) the separation of the lighter from the heavier liquid hydrocarbons; the products resulting from this invention having many advantages and the same may be used for any purposes to which they may be applicable as for example the heavier liquid hydrocarbons product may be employed as a binding medium for use in the manufacture of briquets from coal or other carbonaceous material or for use in the manufacture of ore briquets and for the production of blocks or slabs for paving purposes or said product may be employed for many purposes where pitch and the like is now used.

The present invention consists in treating the aforesaid coal tar (to be separated) by acidulation and the addition of any suitable oil such as hereinafter specified, and stirring the mass until the aforesaid separation is complete and then removing the lighter oils from the heavier oils (or vice versa) in any suitable manner.

We may aerate the residue containing the heavier oils (after separation thereof as aforesaid from the lighter oils) or (and) wash the aforesaid residue containing the heavier oils after separation thereof as aforesaid from the lighter oils.

For the sake of example we will now proceed to describe the treatment of ordinary crude coal tar according to the present invention:—We take coal tar (heated or not; *e. g.* heated to a temperature of say 180° F. or thereabout) and acidulate it in any suitable manner as for example we may add to it a small percentage of sulfuric acid or any other suitable acid (such as hydrochloric acid or nitric acid) which will—as in the case when sulfuric acid is employed—enable the separation to be effected as herein-after explained or we may use chloride of

sulfur. When the acid has been well stirred into the tar (say for about one minute) we then add to the mixture a suitable quantity of any suitable mineral oil such as ordinary mineral illuminating oil (kerosene) fuel oil 60 or petroleum residues, naphtha, petrol, benzol, or the like, or animal or vegetable or fatty oil (all of which we will hereinafter refer to as the “added oil”) and of this added oil we may for example use about (or 65 rather less than) double the quantity of the amount of acid used, say in the proportion of 3 per cent. (by weight) of acid and 4 per cent. (by weight) of the added oil. The stirring is continued and after a few minutes 70 the separation is complete. The lighter oils (which constitute—by weight—about half of the weight of the tar used) can then be poured off, siphoned off, or preferably, taken off with an aspirator; or these lighter 75 oils may be removed from the heavier oils (or vice versa) in any other suitable manner. The lighter oils thus separated and recovered can be sold or otherwise disposed of in any manner desired. The residue containing the heavier oils (thus separated 80 from the lighter oils) may then be placed in a vessel with water (or the water can be added in the vessel in which the heavier oils remain) and are boiled for about half an 85 hour. The result of this boiling is the production of a liquid containing, among other things, a yellow color which may if desired be used as a dye or stain. The resulting colored water or liquid is then run off or separated from the said residue (heavier oils) in 90 any suitable manner and a fresh supply of water is or may then be added in any suitable manner. A second boiling of the mass (for a similar time) may then take place. 95 This second boiling results in the production of a fresh quantum of yellow color in the water which latter can then be separated as before from the said residue and so on; this addition of fresh water to the 100 said residue or washing operation being repeated as often as desired but in practice we have usually found two such washings to be sufficient for removing the greater part of the acid. The result of this process up 105 to this point is to turn the said residue into a substance or material resembling a good liquid pitch or hard pitch as desired, this difference in effect being obtained by slightly varying the percentage of sulfuric 110

acid (or other acid, etc., as aforesaid) used and if desired varying the amount of oil used; while the quality (fluidity or hardness) may be varied by separately heating 5 said substance or material (residue) thereby liberating and removing a further amount of any lighter oils remaining therein. The residue (heavier oils) thus treated resembles in some respects ordinary liquid 10 or soft pitch or hard pitch as the case may be, but this product has (*inter alia*) the distinguishing feature that its melting point is higher and with the hard pitch very much higher while in the case of the softer pitch 15 it is more resilient. Before washing the said residue (heavier oils) as aforesaid or instead of washing the said residue as aforesaid we may aerate the said residue in any suitable manner as for example after the 20 lighter oils have been separated as aforesaid the residue (containing the heavier oils) is heated until it becomes liquid and we may then aerate the said residue in any suitable manner and by any suitable means for 25 instance we may force atmospheric air or steam or any suitable gas or gases (such as oxygen) or mixture of any of these under pressure into the heated residue in order to eliminate the sulfur therefrom or assist in 30 eliminating the same. As a result of the foregoing process there is produced a material from which the sulfur has been eliminated or sufficiently so as to render such material of great commercial value. In any 35 case where the elimination of sulfur is not necessary then the aforesaid steps of washing or (and) aerating the said residue may be omitted altogether.

40 A suitable apparatus for carrying out the herein described process is illustrated in the accompanying drawing in which—

Figure 1 is a plan and Fig. 2 is a vertical sectional view on line 2—2 of Fig. 1.

45 Referring to the drawings, A is a jacketed pan provided with laterally extending pins or trunnions E carried in journals or bearings in the standards J; said jacketed pan A being so arranged that it can be tipped or tilted when desired by freeing the pan 50 from the catches or securing devices I and releasing the clutch or joint H.

55 Any suitable heating medium may be caused to circulate or employed in the jacket space of the pan A; as for example steam may be employed and such steam may be admitted through the inlet pipe C and flexible pipe or hose C¹; and furthermore steam (or air) may be introduced into the interior of 60 said jacketed pan A through the flexible pipe or hose F¹ and the pipe F which latter terminates (as shown) at or near the bottom central part of the pan A; steam being supplied to either or both of these steam inlets C C¹ and F F¹ from any suitable source.

65 The catches or securing devices I I (which

can be attached to and detached from the pan A in any suitable manner) are carried on two fixed standards or strong supports I¹ I¹ which may, for example, be fixed in the concrete floor or carried in the bed 70 plate of the machine.

B B are stirrer arms fixed to and revolved by the vertical shaft B¹ which latter is revolved in any suitable manner as, for example, by the bevel wheel B² thereon operated by the bevel wheel G² on the horizontal shaft G¹, which latter is revolved by the pulley G. 75

In using the illustrated apparatus, the jacketed pan A is filled with tar, for example, so as to just cover the topmost of the stirrer arms B, which latter are caused to slowly revolve and the hereinbefore described acid is added to the tar, for example, said acid is slowly poured into the tar 80 in the pan; heat being applied by the hereinbefore described means. Next kerosene or other lighter hydrocarbon is slowly poured into the acidulated tar and the separation takes place, whereupon the stirrers 85 are stopped and after a time the lighter oils can be separated off, for example, the same may be poured off by releasing the catches I I and disengaging the clutch H and tipping the pan A. After the pan is again 90 fixed, steam may be again turned on into the jacket so as to make the heavy oils (now remaining in the pan) liquid; air or steam being blown through this pitch-like material as, for example, through the pipe F 95 until the acid is mostly removed or neutralized; and the resulting pitch-like material is then discharged from the pan A, e. g. poured into a shallow tank.

100 What we claim is:—

1. The herein described process of treating coal tar for the purpose of separating the lighter from the heavier liquid hydrocarbons therein contained which consists in acidulating the coal tar to be separated and then adding to the mass any suitable oil (such as ordinary mineral illuminating oil, kerosene, fuel oil or petroleum residues, naphtha, petrol or the like, or animal oil or vegetable oil or fatty oil) stirring the 110 mass until the aforesaid separation is complete then removing the lighter oils from the heavier oils (or vice versa) in any suitable manner, and then aerating the residue containing the heavier oils (after the separation thereof as aforesaid from the lighter oils) substantially as and for the purposes hereinbefore described. 115

2. The herein described process of treating coal tar for the purpose of separating the lighter from the heavier liquid hydrocarbons therein contained which consists in acidulating the coal tar to be separated and then adding to the mass any suitable mineral or vegetable oil (such as ordinary min- 120 125 130

eral illuminating oil, kerosene, fuel oil or petroleum residues, naphtha, petrol or the like, or animal oil or vegetable oil or fatty oil) stirring the mass until the aforesaid separation is complete then removing the lighter oils from the heavier oils (or vice versa) in any suitable manner, and then washing the residue containing the heavier oils (after the separation thereof as aforesaid from the lighter oils) substantially as and for the purposes described.

3. The herein described process of treating coal tar for the purpose of separating the lighter from the heavier liquid hydrocarbons therein contained which consists in acidulating the coal tar to be separated and then adding to the mass any suitable mineral or vegetable oil (such as ordinary mineral illuminating oil, kerosene, fuel oil or petroleum residues, naphtha, petrol, or the like, or animal oil or vegetable oil or fatty oil) stirring the mass until the aforesaid separation is complete, then removing the lighter oils from the heavier oils (or vice versa) in any suitable manner, then aerating

the residue containing the heavier oils (after the separation thereof as aforesaid from the lighter oils) and then washing the said residue substantially as and for the purposes described.

30

4. The herein described process for treating coal tar for the purpose of separating the lighter oils from the heavier oils contained therein which consists in acidulating the coal tar with about three per cent. sulfuric acid, adding to the mixture about four per cent. of light mineral oil, stirring the mass until the separation is complete and allowing the whole to settle; drawing off the lighter oils by decanting, aerating the residue containing the heavier oils; and then washing the said residue substantially as and for the purpose hereinbefore described.

35

In witness whereof we have hereunto set our hands in presence of two witnesses.
